FIG. 1

Diagram illustrating a highway ramp system with ultrasonic detection apparatus. The system includes an **ENTERING RAMP** (7) leading to a **FREEWAY** (8). The **FREEWAY** has a **REFLECTING SURFACE** (16) and a **HORIZONTAL DETECTION ZONE** (9). The **REFLECTING SURFACE** is marked with a dashed line and a double-headed arrow. The **HORIZONTAL DETECTION ZONE** is marked with a dashed line and a double-headed arrow. The **FREEWAY** is divided into **LEFT NO TURN** (6) and **LEFT TURN** (10) lanes. The **FREEWAY** ends at an **EXITING RAMP** (19). The **ULTRASONIC DETECTION APPARATUS** (21) is located on the **FREEWAY** and is connected to a **23** (likely a sensor or receiver). The **ULTRASONIC DETECTION APPARATUS** is also connected to a **20** (likely a transmitter or actuator). The **ULTRASONIC DETECTION APPARATUS** is labeled with the text **ULTRASONIC DETECTION APPARATUS**.

APPARATUS FOR DIRECTING VEHICULAR TRAFFIC FLOW

Norman A. Bolton, Scottsville, N.Y., assignor to The General Signal Corporation, Rochester, N.Y., a corporation of New York

Filed Feb. 10, 1964, Ser. No. 343,796
16 Claims. (Cl. 340—31)

This invention relates to apparatus for detecting particular kinds of vehicular traffic movement, and more particularly pertains to apparatus arranged relative to adjacent traffic lanes for detecting vehicular traffic straddling or crossing the boundary between such adjacent traffic lanes and directing such detected vehicles.

The continually increasing use of freeways having adjacent traffic lanes for traffic flow in the same direction with entering ramps and exiting ramps coupled thereto has introduced new conditions of traffic movements which are at times quite hazardous. In this respect, where an entering ramp and an exiting ramp are quite closely coupled to two adjacent traffic lanes of the freeway, a vehicle would have to cross the boundary between such adjacent traffic lanes in order to go from the entering ramp to the exiting ramp. Such crossing of the boundary by traffic presents hazardous traffic movement conditions with respect to traffic movement in the traffic lane coupled to the exiting ramp which could quite easily result in traffic accidents. Another instance in which vehicles cross or straddle adjacent traffic lanes is at an intersection where a traffic signal is controlled for permitting left turn into the intersection. However, unless one or more vehicles actually want to make such a left turn, it is desirable to eliminate such left turn indications from the traffic signal cycle in order to provide the most efficient movement of traffic through the intersection.

Generally speaking, it is contemplated by the present invention to provide apparatus for directing the movement of detected vehicular traffic on freeways in order to minimize hazardous conditions which could otherwise arise. More specifically, it is proposed to so arrange vehicle detection apparatus at a critical point relative to adjacent traffic lanes to detect each vehicle attempting to move from one traffic lane to the other traffic lane. The detection of each vehicle in such vehicle detection zone effects control of a sign or signal for the purpose of directing the movement of that detected vehicle to a particular one of the traffic lanes.

It is contemplated in the present invention to employ as the vehicle detection apparatus an ultrasonic detection system for detecting traffic straddling or crossing adjacent traffic lanes. In brief, an ultrasonic detection system employs sound energy having a frequency in the ultrasonic range such as, for example, eighteen KC per second which is transmitted by a transmitting transducer in the form of either a combined, steady-energy beam or intermittent bursts of energy, for example, toward a receiving transducer contiguous to the boundary of the adjacent traffic lanes. It is proposed in the present invention to position the transmitting transducer above adjacent traffic lanes so as to direct the energy toward a portion of the adjacent traffic lanes from which it is reflected toward the receiving transducer. The ultrasonic detection apparatus acts in response to such reflected energy to provide a normal non-detection indication, but upon interception of such ultrasonic energy by a vehicle such ultrasonic detection apparatus acts to control a traffic directing sign or signal as, for example, the illumination of such sign or signal to suitably direct the movements of that detected vehicle.

2

By employing ultrasonic detection apparatus to define the vehicle detection zone, several advantages immediately accrue. One such advantage is that the transmitting and receiving transducers are located above the traffic lanes and spaced from the actual vehicle detection zone so as to provide access of vehicles of all sizes and shapes to the vehicle detection zone whether or not they are actually permitted therein. Another advantage is that the positioning of the transmitting and receiving transducers with respect to a predetermined reflecting portion of the adjacent traffic lanes is quite variable so that the present system can accommodate any number of different applications where it is desired to provide a vehicle detection zone relative to adjacent traffic lanes. In this respect, the energy transmitted from the transmitting transducer strikes the reflecting portion of the adjacent traffic lanes at an angle of incidence depending upon the position of such transmitting transducer with such energy being reflected from such reflecting portion at an angle of reflection corresponding to the angle of incidence. As long as the receiving transducer is positioned in alignment with the energy reflected at its angle of reflection, proper operation of the system can be had.

One of the advantages inherent in the illumination of a sign or signal for directing vehicular traffic movement is that the motorist's attention is quickly directed to that sign or signal. In response to the sign or signal indication which arrests the motorist's attention, a generally more favorable reaction by the motorist results such that possible hazardous conditions of traffic movement is minimized.

It is thus one object of this invention to provide detection apparatus positioned to define a vehicle detection zone relative to the boundary of adjacent traffic lanes for directing the movements of all vehicular traffic entering such detection zone.

Another object of this invention is to provide detection apparatus having a transmitting transducer and a receiving transducer which are variably positionable with respect to a predetermined portion of adjacent traffic lanes at their boundary to define a detection zone having an area sufficient for detecting all vehicles entering that predetermined portion of adjacent traffic lanes.

Another object of this invention is to provide vehicle detection apparatus positioned for detecting all vehicular traffic entering a predetermined portion of adjacent traffic lanes at their boundary for altering the operation of other existing traffic direction signals adjacent thereto.

Other objects, purposes and characteristic features of the present invention will in part be disclosed in the drawings, and in part be pointed out as the description of the invention progresses.

In describing the invention in detail, reference will be made to the accompanying drawings in which:

FIG. 1 is a diagrammatic view illustrating the vehicle detection apparatus of the present invention positioned for defining a vehicle detection zone on a freeway;

FIG. 2 diagrammatically illustrates a side view of the relative positioning of the transmitting and receiving transducers with a predetermined portion of the adjacent traffic lanes on such freeway for defining the vehicle detection zone;

FIG. 3 illustrates in block diagram form one embodiment of vehicle detection apparatus for controlling a traffic directing sign; and

FIG. 4 diagrammatically illustrates a typical two phase intersection with which the vehicle detection apparatus of the present invention is employed to control a traffic signal to permit detected vehicles to turn left.

Referring now to FIG. 1, a FREEWAY having two traffic lanes 7 and 8 for vehicular traffic in the same direc-

tion is illustrated. An ENTERING RAMP permits movement of vehicles into traffic lane 7 of the FREEWAY as indicated by arrows 9, while an EXITING RAMP permits the movement of vehicles from traffic lane 8 of the FREEWAY as indicated by arrows 10. In addition, arrows 9 and 10 indicate that traffic may flow on respective traffic lanes 7 and 8 beyond the EXITING RAMP. Where the ENTERING RAMP and EXITING RAMP are located in near proximity, it is often desired to limit traffic movement on the ENTERING RAMP and EXITING RAMP to the traffic lane of the FREEWAY to which it is coupled in order to avoid congestion of vehicular traffic upon the FREEWAY. In this connection, traffic lane 7 on the FREEWAY may have one or more NO LEFT TURN indications printed thereon prior to reaching the area of the EXITING RAMP as shown in FIG. 1.

Lying between traffic lane 7 and traffic lane 8 near the EXITING RAMP, a HORIZONTAL DETECTION ZONE is shown in dotted outline which is defined by ultrasonic detection apparatus. More specifically, ultrasonic energy as referred to above is transmitted in a beam from transmitting transducer T toward a portion of adjacent traffic lanes 7 and 8 which portion is indicated to be a REFLECTING SURFACE from which such ultrasonic energy is reflected toward a receiving transducer R. The width of such ultrasonic beam generally constitutes the width of the HORIZONTAL DETECTION ZONE. The transmitting transducer T is held in an overhead position by a mast or arm 16, while the receiving transducer R is held in an overhead position by a mast or arm 17. The transmitting transducer T and receiving transducer R are electrically coupled as suggested respectively by dotted lines 19 and 20 to ultrasonic detection apparatus 21. Ultrasonic detection apparatus 21 comprises electronic circuits for generating the ultrasonic energy at the frequency of, for example, eighteen kc. per second and for acting on such ultrasonic energy when received, or in the absence of such ultrasonic energy, to control a NO LEFT TURN sign 22 as suggested by dotted lines 23.

Turning now to FIG. 2, a side view showing the relative positioning of a transmitting transducer T and a receiving transducer R relative to the REFLECTING SURFACE is illustrated. Transmitting transducer T is positioned above the FREEWAY a distance D1 which may be in the order of, for example, twenty feet. In addition, transmitting transducer T is spaced from the REFLECTING SURFACE a distance D2. As positioned, transmitting transducer T transmits ultrasonic energy toward the REFLECTING SURFACE of adjacent traffic lanes 7 and 8 so as to cause such energy to strike such reflecting surface at a predetermined angle of incidence *i*. Such ultrasonic energy is then reflected from such reflecting surface at an angle of reflection *r* which corresponds to the angle of incidence *i*. According to the angle of incidence *i* and angle of reflection *r* employed, a predetermined VERTICAL DETECTION ZONE is formed in which all entering vehicles intercept the ultrasonic beam of energy. The receiving transducer R is positioned in alignment with the reflected ultrasonic energy so that such energy may be received by the receiving transducer R in the absence of a vehicle in the vehicle DETECTION ZONE. Receiving transducer R is positioned above the FREEWAY a distance D3 and spaced from the REFLECTING SURFACE a distance D4.

It is contemplated that the distance D1 and D2 for transmitting transducer T are variable according to the particular area of detection required for a given application. For any given set of distances D1 and D2, however, the angle of incidence *i* and angle of reflection *r* will be similar for the selected set of distances. The receiving transducer R may then be positioned in alignment with the reflected ultrasonic energy so as to have its distances D3

and D4 either shorter, the same as, or greater than distances D1 and D2, respectively.

Turning now to FIG. 3, the apparatus of the present invention is shown in block form for controlling the NO LEFT TURN sign 22 according to the non-detection or detection of vehicles in the vehicle DETECTION ZONE. It is here suggested that the ultrasonic detection apparatus is conventional as shown in the prior art. A vehicle relay VR is controlled by ultrasonic detection apparatus 21 according to the non-detection or detection of a vehicle in the vehicle DETECTION ZONE. During non-detection periods, vehicle relay VR is maintained picked up. However, during the detection of a vehicle, vehicle relay VR is dropped away.

For each vehicle detection which causes relay VR to be dropped away, the NO LEFT TURN sign 22 is controlled. In this connection, delay circuit 24 receives control energy through back contact 26 of relay VR during the period that such relay VR is dropped away. Delay circuit 24 is provided for controlling the NO LEFT TURN signal 22 as soon as it is activated upon detection of a vehicle and for a short predetermined interval after such vehicle is no longer detected in order to control the NO LEFT TURN sign 22 for a sufficient duration such that it remains illuminated for a sufficient time period to alert the motorist of that detected vehicle. Delay circuit 24 may be, for example, a conventional one-shot multivibrator.

Turning now to FIG. 4, a two-phase intersection is illustrated which includes a LEFT TURN ONLY traffic lane having a traffic signal S1 associated therewith as well as two additional traffic lanes each having a traffic signal associated therewith, these traffic signals being designated S2 and S3. Local controller apparatus 40 is provided in block form for controlling traffic signals S1, S2 and S3 in any well known manner. In addition, traffic signal lights 32, 33 and 34 are illustrated in block form for the other directions of traffic movement at such intersection and are indicated to be controlled by the local controller apparatus 30 as suggested by dotted line 35.

In the diagrammatic example of FIG. 4, the vehicle detection apparatus of the present invention is employed in conjunction with local controller apparatus 30 in order to operate traffic signal S1 to display a green arrow only if a vehicle is detected as entering the LEFT TURN ONLY traffic lane. More specifically, transmitting transducer T and receiving transducer R are illustrated as being positioned relative to the REFLECTING SURFACE lying between the LEFT TURN ONLY traffic lane and the adjacent traffic lane 36. Transmitting transducer T and receiving transducer R are spaced from such REFLECTING SURFACE and elevated in position above the traffic lanes similar to that shown in FIG. 2 for directing a beam of ultrasonic energy toward the REFLECTING SURFACE from which it is reflected toward receiving transducer R to define a vehicle DETECTION ZONE as shown in FIGS. 1 and 2.

Transmitting transducer T and receiving transducer R are electrically coupled to ultrasonic detection apparatus 21 as suggested by dotted lines 19 and 20 respectively for operating relay VR in the manner described above for FIG. 3. Operation of relay VR controls a memory device 42 through its contact 26. More specifically, (+) energy is electrically coupled through back contact 26 of relay VR during detection of a vehicle in the vehicle DETECTION ZONE to operate memory device 42 to its abnormal condition of operation. In its abnormal condition of operation, memory device 42 controls local controller apparatus 30 as suggested by line 43 for the purpose of modifying its cycle operation to the extent that signal S1 is controlled to display a green arrow indication to traffic in the LEFT TURN ONLY lane for permitting the detected vehicle to move through the intersection. In order that memory device 42 be reset to its normal condition of operation, it is suggested that local controller apparatus

30 be effective at or near the end of its cycle during which it controls signal S1 to display a green arrow indication to control memory device 42 as suggested by line 44.

The feature of resetting the memory device 42 by the local controller apparatus 30 at or near the end of its cycle permits the memory device 42 to be operated to its abnormal condition of operation by a vehicle detected after the cycle of the local controller apparatus 30 is completed. Upon return of operation of local controller apparatus 30 during its next cycle to that part of such cycle in which signal S1 may be controlled to display its green arrow indication, local controller apparatus 30 is again controlled by memory device 42 for controlling signal S1.

Although it is suggested herein to employ only a single transmitting transducer T and a single receiving transducer R for defining the vertical detection zone, it is contemplated that a plurality of transmitting transducers T and a plurality of receiving transducers R could be employed where a substantially longer vehicle DETECTION ZONE is desired. For example, a plurality of pairs of transmitting transducers T and receiving transducers R may be employed with each such pair tuned to a different frequency and so mounted in position above adjacent traffic lanes as to cause the transmitted energy of different frequencies to be reflected from predetermined reflecting surfaces to the correspondingly tuned receiving transducers.

Having shown and described apparatus for directing vehicular traffic flow as one embodiment of the present invention, it is to be understood that this embodiment has been selected to facilitate in the disclosure of the invention rather than to limit the number of forms which it may assume; and it is to be further understood that various modifications, adaptations and alterations may be applied to the specific embodiment shown to meet the requirements of practice without in any manner departing from the spirit or scope of the present invention.

1. A system for detecting vehicles straddling the boundary between two adjacent traffic lanes comprising, in combination,

- (a) first nonobstructing means for transmitting a predetermined signal contiguous to said boundary a pre-determined distance substantially in alignment with the flow of vehicular traffic in said two adjacent traffic lanes,
- (b) second nonobstructing means for receiving said predetermined signal until a vehicle straddles said boundary within said predetermined distance and intercepts said predetermined signal,
- (c) means responsive to said second nonobstructing means for each period during which said signal is absent therefrom for indicating detection of the vehicle intercepting said predetermined signal.

2. A system for detecting vehicles straddling the boundary between two adjacent traffic lanes comprising, in combination,

- (a) first means located in relation to said boundary nonobstructive to traffic flow for transmitting a predetermined signal contiguous to said boundary in alignment with the flow of vehicular traffic in said two adjacent traffic lanes,
- (b) second means located in relation to said boundary nonobstructive to traffic flow and opposite to said first means for receiving said predetermined signal continuously except for the period each vehicle crosses said boundary and intercepts said predetermined signal,
- (c) means responsive to said second means for each said period for indicating detection of the vehicle intercepting said predetermined signal.

3. The system according to claim 2 in which said first means includes directing means for directing said signal contiguous to said boundary in a narrow beam, whereby each of the vehicles travelling in said two traffic lanes intercepts such signal only when it straddles said boundary.

4. The system according to claim 3 wherein said first means and said second means comprise an ultrasonic detection system in which said predetermined signal is ultrasonic energy generated by said first means and directed in the narrow beam by said directing means and received by said second means unless intercepted by a vehicle straddling said boundary.

5. The system according to claim 4 in which said ultrasonic energy as generated is a continuous signal.

6. The system according to claim 4 in which said ultrasonic energy as generated is intermittent in the form of ultrasonic energy bursts.

7. A system for detecting vehicles crossing the boundary between two adjacent traffic lanes comprising, in combination,

- (a) first means aligned with said boundary for directing a signal transmitted thereby toward said boundary from which said signal is reflected unless intercepted by a vehicle,
- (b) second means aligned with said boundary and on the side of the reflecting portion of said boundary opposite to said first means for receiving such reflected signal,
- (c) means responsive to said second means during each interval thereof in which said signal is absent for indicating detection of the vehicle crossing said boundary and intercepting said signal.

8. The system according to claim 7 in which said first means includes a transmitting element suspended above said boundary a distance greater than the highest vehicle travelling on said two adjacent traffic lanes for directing said signal toward said boundary, said second means having a receiving element suspended above said boundary a distance also greater than the highest vehicle travelling on said two adjacent traffic lanes and on the side of said reflecting portion opposite to said transmitting element, whereby any vehicle may pass beneath said transmitting element or said receiving element along said boundary.

9. The system according to claim 8 in which the distance of said transmitting element above said boundary is equal to the distance of said receiving element above said boundary and the longitudinal distances of said transmitting element and receiving element from the reflecting portion are equal.

10. The system according to claim 8 in which the distance of said transmitting element above said boundary and its longitudinal distance from said boundary are unequal respectively with the distance of said receiving element above said boundary and its longitudinal distance from said boundary, said receiving element being disposed in the path of said signal as reflected from said portion of said boundary unless such signal is intercepted by a vehicle.

11. A system for detecting vehicles straddling the boundary between two adjacent traffic lanes comprising, in combination,

- (a) first means positioned above said boundary for directing a transmitted signal toward a particular portion of said two adjacent traffic lanes including the boundary therebetween from which said signal is reflected,
- (b) second means positioned above said boundary and from the side of said portion opposite to said first means for receiving said transmitting signal reflected from said portion except for the period each vehicle straddles said boundary including said portion and intercepts said signal, and
- (c) means responsive to said second means for each such period for indicating detection of the vehicle intercepting said signal.

12. A system for detecting vehicles crossing the boundary between two adjacent traffic lanes and directing the movements thereof comprising, in combination,

- (a) first nonobstructing means for transmitting a predetermined signal contiguous to said boundary sub-

- stantially in alignment with the flow of vehicular traffic in said two adjacent traffic lanes,
- (b) second nonobstructing means for receiving said predetermined signal until a vehicle crosses said boundary and thereby intercepts said predetermined signal, and
- (c) traffic direction means positioned relative to at least one of said two traffic lanes and responsive to said second means for each period during which said signal is absent therefrom for providing an indication to direct the movement of the detected vehicle.
13. The system according to claim 12 wherein said first nonobstructing means and said second nonobstructing means comprise an ultrasonic detection system in which said signal is ultrasonic energy generated by said first nonobstructing means and directed in a beam contiguous to said boundary generally toward said second nonobstructing means until said signal is intercepted by a vehicle, at least one of said two traffic lanes having a traffic lane coupled thereto, said traffic direction means including a sign effective to display a distinctive indication when said traffic direction means is controlled to direct the movement of the detected vehicle away from such coupled traffic lane, said sign being responsive to said second nonobstructing means for each interval that said signal is intercepted by a vehicle.

14. The system according to claim 13 in which said second nonobstructing means includes delay means responsive during each interval that said signal is intercepted by a vehicle for controlling said sign for a predetermined interval after the detected vehicle no longer intercepts said signal.

15. The system according to claim 12 wherein said first nonobstructing means and said second nonobstructing means comprise an ultrasonic detection system in which said signal is ultrasonic energy generated by said first nonobstructing means and directed in a beam contiguous to said boundary generally toward said second nonobstructing means until said signal is intercepted by a vehicle, said two traffic lanes being included in an intersection of traffic lanes having at least two other traffic lanes for oppositely flowing traffic transverse thereof, said traffic direction means including traffic directing signals and means for controlling said signals through predetermined cycles of operation, said means being responsive to said second nonobstructing means at least during the interval a vehicle
- 10
- 15
- intercepts said signal to control one of said traffic directing signals to a proceed aspect for a predetermined interval for directing the detected vehicle to turn onto one of said two other traffic lanes.

16. The system according to claim 15 in which said second nonobstructing means includes a memory means controlled to a storage condition responsive to said second nonobstructing means upon interruption of said signal by a vehicle for controlling said means causing it to effect control of said one traffic directing signal, said means being effective at substantially the termination of said predetermined interval to control said memory means to a non-storage condition.
